Attorneys.

UNITED STATES PATENT OFFICE.

GEORGE W. BRIGGS, OF NANUET, NEW YORK.

PLIERS.

Application filed August 28, 1926. Serial No. 132,151.

One object of this invention is to provide a tool which will combine the advantages of a pair of round nosed pliers, a pair of flat jawed pliers, and a pair of side-cutters.

5 Another object of the invention is to provide a pair of pliers which will be peculiarly effective in holding round objects without marring them, it being possible to hold objects of different diameters, with the handles 10 of the pliers spaced at about the same distance apart, thereby keeping the handles of the pliers close enough together so that they can be gripped readily.

It is within the province of the disclosure to improve generally and to enhance the utility of devices of that type to which the invention appertains.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, may be made within the scope of what is claimed, without departing from the spirit of the invention.

In the drawings:—

Figure 1 shows in side elevation, a pair of 30 pliers constructed in accordance with the invention;

Figure 2 is an elevation wherein the pliers are viewed edgewise;

Figure 3 is a view similar to Figure 2, 35 parts being broken away and parts being in section;

Figure 4 is a diagrammatic cross sectional view illustrating how the tool is used in holding round objects; and

40 Figure 5 is a fragmental side elevation, the opposite side of the tool appearing from that which is shown in Figure 1.

In carrying out the invention there is 45 provided a pair of pliers comprising pivotally connected handles 4. Each handle 4 is provided with a first jaw 1 and with a second jaw 2. The jaws 1 and 2 are located side by side, as shown in Figure 4. The first jaws 1 are of polygonal cross section and are disposed opposite to each other. The second jaws 2 are of approximately circular cross section, to provide curved sur-

faces 3 thereon. The second jaws 2 are disposed opposite to each other. The first jaws 1 have pronounced inner longitudinal edges 55 5. The edges 5 of the jaws 1 cooperate with the curved surfaces 3 of the second jaws 2, to hold an object 6. The cylindrical surfaces 3 serve to engage the object 6 without marring it. Each of the second jaws 2 is 60 in the form of a cone, and one element 7 of each cone forms an acute angle 8 with respect to one of the inner longitudinal edges 5 of the first jaws 1, the word "element" 65 being used in its mathematical sense. The construction last above described is such that objects of different diameters may be held in the position of Figure 4, without changing the distance between the handles, and the handles are always at the right distance 70 apart so that they can be gripped and held conveniently. The handles 4 are crossed on each other, as at 10, and the pivot element which connects them is marked by the numeral 11. The portions of the pliers which 75 carry the jaws 1 may be provided with co-operating cutting edges 12, giving the tool all of the advantages of a side cutter.

I claim:—

80 A pair of pliers comprising pivotally connected handles each provided with a first jaw and with a second jaw, located side by side, the first jaws being of polygonal cross section and being disposed opposite to each other, the second jaws being of approximately circular cross section to provide curved surfaces thereon, the second jaws being disposed opposite to each other, the first jaws having pronounced inner longitudinal edges which cooperate with the curved surfaces of the second jaws to hold an object, 85 the said cylindrical surfaces serving to engage an object without marring it, the second jaws each being in the form of a cone, and one element of each cone forming an acute angle with respect to one of said inner longitudinal edges of the first jaws, thereby to enable the holding of objects of different diameters without changing the distance 90 between the handles.

95 100 In testimony that I claim the foregoing as my own, I have hereto affixed my signature.

GEORGE W. BRIGGS.
